UNITED STATES PATENT OFFICE

116,161

DESIGN FOR A SADIRON OR THE LIKE

William E. Gundelfinger, St. Louis, Mo., assignor to Knapp-Monarch Company, St. Louis, Mo., a corporation of Missouri

Application June 12, 1939, Serial No. 85,452

Term of patent 7 years

To all whom it may concern:

Be it known that I, William E. Gundelfinger, a citizen of the United States and a resident of St. Louis, in the State of Missouri, have invented a new, original, and ornamental Design for a Sadiron or the like, of which the following is a specification, reference being had to the accompanying drawing, forming a part thereof.

The dominant features of my design reside in the parts shown by solid lines in the drawing.

I claim:

The ornamental design for a sadiron or the like, substantially as shown and described.

WILLIAM E. GUNDELFINGER.
